Des. 1165

Allen Leonard, of Hartford, Conn.
Letters Patent No. 1165. Dated Nov. 1. 1859.

The schedule referred to in these Letters Patent, and making part of the same.

To all whom it may concern:

Be it known that I, Allen Leonard, of the City and County of Hartford, and State of Connecticut, have invented or produced a new and Original Design for a Handle or lift, for Casters &c. and I do hereby declare that the following is a full, and exact description of the same.

In the accompanying drawings or Photographs, is shown a rich and ornamental design of a Handle or lift for Casters &c.

A. is the post or column.

B. the lifting ring capped with a row of graduated beads, and supported by the column and foliage of leaves and branches of an artistically-worked figure or configuration thereon, for a Handle or lift for Caster &c.

What I claim and desire to secure by Letters Patent, is the configuration of a tasteful and artistical wrought figure for an ornamental design, for a Handle or lift, substantially as described, for a Caster &c.

Witnesses.

Edward M. Bliss,
G. M. P. Jeremy W. Bliss.

Allen Leonard.
